UNITED STATES PATENT OFFICE.

HIRAM C. FONDE, OF BIRMINGHAM, ALABAMA.

HEATER.

1,206,427.

Specification of Letters Patent. Patented Nov. 28, 1916.

Application filed January 11, 1916. Serial No. 71,562.

To all whom it may concern:

Be it known that I, HIRAM C. FONDE, a citizen of the United States, residing at Birmingham, in the county of Jefferson and State of Alabama, have invented a new and useful Heater, of which the following is a specification.

The device forming the subject matter of this application is a wood burning heater adapted to be assembled with a bath tub, for the double purpose of heating water which is to be discharged into the bath tub and heating the room wherein the bath tube is located.

The present invention aims to provide, in a device of the type described, a novel form of coil which will present a maximum amount of area to the fuel, thereby economizing the fuel.

It is within the province of the disclosure to improve generally and to enhance the utility of devices of that type to which the present invention appertains.

With the above and other objects in view which will appear as the description proceeds, the invention resides in the combination and arrangement of parts and in the details of construction hereinafter described and claimed it being understood that changes in the precise embodiment of the invention herein disclosed can be made within the scope of what is claimed, without departing from the spirit of the invention.

In the accompanying drawing, the invention is shown in a single vertical sectional figure.

In carrying out the present invention there is provided a heater embodying an ash pit 1 supported on legs 2 and provided with an ash door 3, the ash pit 1 containing an ash pan 4. Supported on the ash pit 1 is a base 5 upholding a drum 6 preferably of circular contour, the drum 6 being provided adjacent its bottom with a lighting door 7. Supported by the drum 6 is a top 8 having an opening 9 closed by a removable cap 21. The grate is indicated by the reference character 20. The top 8 carries a collar 10 co-operating with a flue 11.

Disposed within the drum 6 is a spiral coil of pipe 12, the lower end of which opens into an inlet 14 projecting outwardly through the drum near to the bottom of the drum.

The upper end of the coil 12 communicates with a vertical, U-shaped extension 15 lying within the flue 11 and embodying a depending arm 16 extended downwardly within the contour of the coil 12, to a point adjacent the bottom of the coil. The arm 16 communicates with a lateral pipe 17 extended outwardly through the drum 6 and entering the bath tub 18, the pipe 17 being terminally equipped with a cock 19.

In practical operation, combustible material, ordinary wood, is introduced into the heater within the contour of the coil 12. When this combustible material is lighted, water passing through the coil will be heated rapidly and, at the same time, the apartment wherein the bath tub 18 is located, will be heated also. The present invention, therefore, provides means whereby, through the instrumentality of a single heater, water delivered to a bath tub, and the air in the apartment wherein the bath tub is located may be warmed. Owing to the fact that the coil 12 communicates with the U-shaped pipe 15, the latter, lying within the flue 11, will increase the amount of heating surfaces provided and, at the same time, render it possible, to locate both the inlet and the outlet end of the coil adjacent the bottom of the heater.

Having thus described the invention, what is claimed is:—

In a device of the class described, a heater comprising a drum; a coil within the drum and comprising superposed convolutions, the lower convolution of the coil opening laterally through the heater adjacent the bottom of the heater; a flue assembled with the heater; and a U-shaped pipe connected with the upper convolution of the coil and projecting upwardly into the flue, the U-shaped pipe embodying a depending arm extended downwardly within the contour of the coil to a point adjacent the bottom of the heater, and prolonged outwardly to a point beyond the heater.

In testimony that I claim the foregoing as my own, I have hereto affixed my signature in the presence of two witnesses.

HIRAM C. FONDE.
